PASTE BRUSH HOLDER

Vincent S. Aquino, Worcester, Mass.

Application August 29, 1955, Serial No. 37,682

Term of patent 14 years

(Cl. D9—2)

Fig. 1 is a perspective view on a reduced scale of a paste brush holder showing my new design;

Fig. 2 is a perspective view taken from the left of Fig. 1;

Fig. 3 is an end elevational view from the right of Fig. 2;

Fig. 4 is a bottom perspective view;

Fig. 5 is a side elevational view taken from left of Fig. 3;

Fig. 6 is a bottom plan view; and

Fig. 7 is another side elevational view taken from the right of Fig. 3.

The dotted line showing of a bucket and brush in Fig. 1 is for the purposes of illustration only.

I claim:

The ornamental design for a paste brush holder, substantially as shown and described.
